TERMINAL FOR AN ELECTRICAL ELEMENT

Fred J. Fuller, Chicago, Ill., assignor, by mesne assignments, to P. R. Mallory & Co., Inc., a corporation of Delaware

Application March 2, 1959, Serial No. 54,790

Term of patent 14 years

(Cl. D26—9)

Figure 1 is an elevational view of a terminal for an electrical element, showing my new design;

Figure 2 is an elevational view taken at right angles to the view of Figure 1;

Figure 3 is a bottom plan view;

Figure 4 is a top plan view;

Figure 5 is a section taken generally along line 5—5 of Figure 1;

Figure 6 is a section taken generally along line 6—6 of Figure 1; and

Figure 7 is a section taken generally along line 7—7 of Figure 1.

I claim:

The ornamental design for a terminal for an electrical element, as shown.
